UNITED STATES PATENT OFFICE.

HARRY ARTHUR FOOTHORAP, OF HARRISBURG, PENNSYLVANIA, ASSIGNOR TO ELLIOTT-FISHER COMPANY, OF HARRISBURG, PENNSYLVANIA, A CORPORATION OF DELAWARE.

TYPEWRITING-MACHINE.

1,383,096.

Specification of Letters Patent. Patented June 28, 1921.

Original application filed December 14, 1914, Serial No. 877,216. Divided and this application filed August 17, 1918. Serial No. 250,316.

To all whom it may concern:

Be it known that I, HARRY ARTHUR FOOTHORAP, citizen of the United States of America, residing at Harrisburg, in the county of Dauphin and State of Pennsylvania, have invented certain new and useful Improvements in Typewriting-Machines, of which the following is a specification.

This invention relates to a novel line 10 finder mechanism adapted more particularly for use in connection with machines of that type characterized by a stationary platen and downwardly acting printing mechanism.

The mechanism shown in the accompanying drawings is also shown and described in applicant's copending application for Letters Patent of the United States Serial No. 877,216, filed Dec. 14, 1914, of which this is a division. Only so much of the mechanism 15 disclosed in said copending application as is necessary to the understanding of the features of the invention claimed herein is shown and described in the present application. For a complete description of the 20 mechanism herein shown and its associated parts reference may be had to said copending application.

The object of the invention, speaking generally, is to provide an efficient and economical line finder for a flat platen typewriter of 25 the visible writing type.

In the accompanying drawings:

Figure 1 is a front elevation of an Elliott-Fisher billing machine carriage provided 30 with my line finding mechanism.

Fig. 2 is a vertical section through the same showing the line finding mechanism in side elevation.

Fig. 3 is a bottom plan view of the same. 40 Fig. 4 is an enlarged vertical section of the same showing in dotted lines the finder advanced to the printing point.

Fig. 5 is a perspective view of the line 45 finder and its operating means attached to a portion of the carriage frame.

Fig. 6 is a detail perspective of the line 50 finder.

Fig. 7 is an enlarged plan view of the line 55 finder.

Fig. 8 is a detail perspective view of the 60 ribbon vibrator bracket.

Fig. 9 is a similar view of the vibrator.

The machine to which my invention is shown applied is what is known as the Elliott-Fisher billing machine which is of 55 that type in which the platen is stationary and above which moves longitudinally a line space frame supporting a carriage which is movable transversely of the platen to letter space the writing accomplished by a downwardly acting printing mechanism mounted 60 on and movable with said carriage.

By reference to my copending application, Serial No. 877,216, it will be seen how the ribbon is supported by the two ribbon spools 65 located at opposite sides of the machine adjacent to its rear, how it is guided to and across the machine, and how its feed is effected and controlled.

To the under side of the front bar 3^a of 70 the type ring 3 is screwed or otherwise secured, immediately opposite the printing point, a guide bracket 4 substantially U-shape in cross section and serving as a combined vibrator and line finder guide. From the vertical side of the bracket 4 a pair of parallel arms 5 extend rearwardly, connected at their rear ends by the camming and guiding bar 6 of a line finder, to be described, and supporting a pair of rearwardly extended and laterally deflected supporting 75 and guiding fingers 7 having vertically disposed front ends 8 having oppositely opening kerfs 9 in their outer edges. These kerfs or notches 9 are designed for the reception 80 of the guide flanges 10 of the ribbon vibrator 11 and occupying a horizontal plane somewhat elevated, relative to the depressed body portion of the vibrator. The guide flanges 10 are formed by bending into a horizontal 85 plane the upper edge of a pair of inclined ribbon guides 12 formed at the opposite sides of the rear end of the vibrator and disposed at opposite angles at substantially 90 forty-five degrees. Disposed opposite the outer or under side of each of these ribbon guides 12 are a pair of oppositely disposed ribbon fingers 13 under which the ribbon is 95 lead and which not only retain the ribbon snugly against the vibrator and depressor, but also compel the ribbon to move laterally 100 with the vibrator as the latter is operated in the manner to be described. The body portion of the ribbon vibrator is of sub-

stantial U-shape to afford an opening between the ribbon guides for accommodation of the type bars and has a forwardly extended, somewhat elevated slide 14, the side edges of which are slidably received within kerfs 15 and the downturned extremities of the front supporting and guiding fingers 16 extended forwardly from the bottom of the bracket 4. The slide 14 is provided with suitable stops 17 and 18 which engage the supporting structure and limit the sliding movement of the vibrator.

Mounted on the front bar 3^a of the type ring 3 is a line finder shaft 19 accommodated by bearing brackets 20 secured to the bar. At its inner end, the shaft 19 is provided with an arm 21 pivotally connected to the rear end of the line finder 22 which constantly tends to move upward under the impulse of a spring 23 located in the connection between the arm and finder. This spring holds the finder against the under side of the bar 6 and in a sufficiently elevated position to prevent interference with the ribbon. The body portion of the line finder, however, is cam-shape or longitudinally curved so that when the lower end of the arm 21 is swung rearwardly the line finder is urged rearwardly and at the same time its rear end is elevated.

The result of these peculiarities of form and movement is to cause the rear end of the line finder to move back and downward to the printing point, the usual notch in its rear edge serving to locate the exact point of printing. At its outer end the line finder shaft 19 is provided with an arm 24 which is disposed vertically and has its upper end in operative relation to the lower end of an arm 25 of a rock shaft 26 mounted in the carriage casing adjacent to its front left hand corner, as for instance, in a bracket 27 and having a short arm 28 connected to the inner end of the stem 29 of the line finder key 30, said stem extending through the front of the carriage casing, as shown.

It is thought that from the foregoing, the construction and operation of the described embodiment of my invention will be clearly understood, but I wish distinctly to reserve the right to effect such changes, modifications or variations of the illustrated structure as may fall fairly within the scope of the protection prayed.

What I claim is:—

1. In a typewriter, the combination with a stationary platen, of a line finder normally withdrawn from the line, means for moving the line finder toward the line of writing and means effective during such movement to urge the line finder toward the platen.

2. In a typewriter, the combination with a platen, of a line finder movable longitudinally toward and from the line of writing and means for camming the line finder laterally toward the platen during this movement toward the line. 65

3. In a typewriter, the combination with a stationary platen, of a swinging arm, a line finder pivoted on the arm, means for 70 swinging the arm to advance the line finder longitudinally and means operated during such advance to swing the line finder relative to the arm and laterally into close proximity to the platen.

4. In a typewriter, the combination with a stationary platen, of a swinging arm, a line finder pivoted to the arm, a spring tending to urge the line finder away from the platen, means for swinging the arm to advance the line finder and means for urging the line finder toward the platen in opposition to the spring. 80

5. In a typewriter, the combination with a platen, a line finder having the form of a 85 cam, means for moving the line finder toward the line and a fixed part coacting with the line finder during such movement to cam the line finder toward the platen.

6. In a typewriter, the combination with 90 a platen, of a movable line finder support, a fixed bar, a cam shaped line finder carried by the support and coacting with the bar and means for moving the support.

7. In a typewriter, the combination with 95 a platen, of a swinging arm, a cam shaped line finder swung from the arm, a fixed bar coacting with the line finder to cam the latter toward the platen, a spring tending to urge the line finder away from the platen 100 and into engagement with the bar and means for swinging the arm to advance the line finder and to cause the same to be urged toward the platen in opposition to the spring. 105

8. In a typewriter, the combination with a type ring having a front bar, of a line finder support carried by the bar and a line finder carried by the support and movable toward and from the printing point. 110

9. In a typewriter, the combination with a type ring having a bar, of a guide bracket carried by the bar, a vibrator guided by the bracket, a cam shaped line finder and a camming bar carried by the bracket and coacting 115 with the line finder.

In testimony whereof I affix my signature in the presence of two witnesses.

HARRY ARTHUR FOOTHORAP.
